CENTRIFUGAL TRANSFER SWITCH

Filed May 10, 1929

Fig. 1.

UNITED STATES PATENT OFFICE

HARRY D. ELSE, OF SPRINGFIELD, MASSACHUSETTS, ASSIGNOR TO WESTINGHOUSE ELECTRIC & MANUFACTURING COMPANY, A CORPORATION OF PENNSYLVANIA

CENTRIFUGAL TRANSFER SWITCH

Application filed May 10, 1929. Serial No. 361,870.

My invention relates to induction motors and particularly to centrifugally-actuable switches therefor.

An object of my invention is to provide a relatively simple, inexpensive and easily manufactured and installed centrifugally-actuable switch to be operatively associated with an induction motor of the split-phase or capacitor type.

Another object of my invention is to provide a relatively simple, centrifugally-actuable switch embodying a minimum number of parts, the engagement and disengagement of the cooperating contact members being effected with a snap action.

In practicing my invention, I provide a substantially fixed base plate having a plurality of laterally bent slotted guide portions thereon, a two-part carriage movable in said slotted guide portions, a pair of toggle-joint members operatively connecting the parts of the carriage of the base plate, a spring connecting the two parts of the carriage, and fixed contact members on the base plate, and a movable contact arm or switch member on one of the parts of the carriage.

In the single sheet of drawings,

Figure 1 is a view, in front elevation, of a switch assembly embodying my invention, shown in one of its limiting operative positions.

Fig. 2 is a view, in front elevation, of the same device shown in the other of its limiting positions.

Fig. 3 is a view, in front elevation, of one detail of the switch.

Fig. 4 is a view, in end elevation, of the switch assembly embodying my invention.

Fig. 5 is an exploded view, taken in end elevation, of a switch embodying my invention and a centrifugally-actuable weight assembly for actuating the switch.

Fig. 6 is a view, in front elevation, of the centrifugally-actuable weight-member assembly, and

Fig. 7 is a schematic diagram of connections of an induction motor with which the device embodying my invention may be operatively associated.

A centrifugally-actuable switch embodies

a base plate 11 which is of substantially rectangular shape in outline and has an opening 12 in its central portion in order that it may be located around the shaft of an induction motor. A plurality of laterally extending guide portions 13 and 14 are provided, each of these guide portions having a slot 16 therein.

While no specific structure is shown for supporting the base plate 11, it is to be understood that it will be supported by or from the stator structure of the motor in which it is mounted and with which it is operatively associated. One or more openings 17 may be provided in the body portion of the base plate 11 in order that it may be secured in proper operative position.

A plate 18 of electric-insulating material is mounted on one part and one face of the base plate 11 between the guide portions 14, and has mounted thereon a plurality of fixed contact members 19, 21 and 22. The contact members 19 and 21 may be of substantially L-shape, one leg portion thereof being secured against the plate 18 while the other portion thereof extends laterally therefrom. The contact member 22 may be of substantially U-shape, as is shown more particularly in Fig. 4 of the drawings, and may be secured against plate 18 by any suitable or desired means, here shown as by a plurality of rivets 23. Similar securing means may also be employed for securing the contact members 19 and 21 in position.

A two-part carriage, movable relatively to the base plate 11, in a plane parallel thereto and spaced therefrom, includes a part 24 and a second part 26, which may be made of punched and formed sheet-metal plate.

The part 24 is, in general, of L-shape and includes outer or side portions 27 and 28 which are adapted to be located and moved in the slots 16 of the guide portions 13. Upstanding or laterally bent lugs 29 and 31 are made integral with the part 24 and are of substantially arcuate shape, for a purpose to be hereinafter set forth.

The second part 26 of the carriage, is also of L-shape, in general, although the one leg portion thereof is relatively short. The part

26 is adapted to fit and move in the slots 16 of the guide portions 14.

A pair of toggle joints, each including relatively stiff and inflexible bar members 32 and 33, is provided, the members 32 respectively extending between the end portions 27 and 28 of the part 24 and a pair of laterally-bent lug portions 34 and 36 which are integral with the base plate 11. Recesses are 10 provided in the members 24 and 26 and in the lugs 34 and 36 in order that the toggle-joint members 32 and 33 may interfit therewith. A spring 37 extends between the left-hand ends of the parts 24 and 26 and is, therefore, effective to yieldingly pull the two parts 24 and 26 of the carriage toward each other, 15 against the pairs of toggle joint members 32 and 33.

A switch arm 38 is loosely mounted on the 20 part 26 and comprises a resilient bar or strip of metal having contact members 39 secured thereto at the outer end thereof and a pair of contact members 41 mounted thereon at the inner end thereof. The member 38 is provided with an opening 42, intermediate its 25 ends, in order that a pair of relatively thin strips 43 and 44, of insulating material, may extend therethrough and be secured against the opposite faces of the part 26 of the carriage. The members 43 and 44 are severally 30 provided with recesses in opposite edges, substantially midway of the lengths thereof, and are suitably secured against the member 26 by rivets 46. The particular outline of the opening 42 is provided in order that the parts 43, 44 and 26 may be assembled in the 35 relative positions shown in the drawings to extend through the member 38.

Means for insuring positive operation of 40 the part 26 of the carriage by the part 24 thereof, comprises a recess 47 in the part 26 and a lug 48 on that arm of the part 24 which extends toward the part 26, and the action thereof will be hereinafter described in detail.

Any desired type of centrifugally actuatable 45 weight member may be provided, one form of such structure being shown in Figs. 5 and 6 of the drawings. I have there shown a motor shaft 51 on which is mounted a disc 52 having a plurality of springs 53 extending parallel to its face and, therefore, at substantially right angles to the axis of the shaft 51. A plurality of weight members 54, 50 here shown as three in number, are provided and are so mounted relatively to the disc 52 and arms 56 extending therefrom, and relatively to the springs 53, as to be moved radially outward when a predetermined speed 55 of the rotor shaft 51 is exceeded. Conversely, the weight members 54 will move radially inward when the speed falls below said predetermined value. While I have illustrated and 60 described a specific embodiment of a centrifugally actuatable structure, I do not desire to

be limited thereto, this structure being shown for purposes of illustration only. It is to be understood, however, that the weight members 54 or their equivalents, will move between the lugs 29 and 31 of the part 24 of 70 the carriage and operatively engage either the lug 31 or the lug 29, in accordance with whether the speed is increasing or decreasing.

Referring more particularly to Fig. 7, I have there illustrated a stator structure 61, 75 having mounted thereon a main winding 62 and an auxiliary winding 63, the centrifugally-actuable switch being shown schematically at 64. In this particular illustration, it is obvious that the auxiliary winding 63 80 is to be open-circuited after the motor has been brought to a predetermined speed by the combined action of the two windings, in a manner well known in the art.

However, as will be presently herein set forth, the switch embodying my invention may be used also in connection with capacitor motors in which the capacitance operatively associated with the motor is connected, by means of a transfer switch, to a higher voltage at starting than during the normal running of the motor. However, the switch embodying my invention may be used equally well in interrupting the circuit of a starting winding 63. 95

Let it be assumed that the switch structure embodying my invention is mounted substantially as shown in Fig. 5, except that the two parts are so located relatively to each other that the weight members will interfit 100 with the lugs 29 and 31. If it be assumed that the starting switch of the motor is closed, it is obvious that the rotor will be caused to turn and that, at a predetermined speed of rotation thereof, the weight members 54 will 105 move radially outwardly and engage the lug 31. The position of the carriage, up to this time, will be that shown in Fig. 1 of the drawings, and, upon the aforesaid engagement of the weight members and the lug 31, 110 the part 24 will move toward the right, as viewed in the drawings, the movement of this part being directly in accordance with the movement, in a radially outward direction, of the weight members 54. The spreading 115 apart of the parts 24 and 26 of the carriage, required by the relatively stiff and unyielding toggle-joint members 32 and 33, will be permitted by reason of the spring 37, and the part 24 will, therefore, move in a plane parallel to itself. No movement of the part 26 of the carriage will result until the axis of the spring 37 is substantially parallel to the toggle-joint members 33. As soon as the axis 120 of the spring 37 has moved so far as to be slightly beyond such parallelism, the part 26 will be moved with a snap action, the general action, therefore, being that of the usual over-center spring and toggle-joint combination. 125

The switch arm 38 will, therefore, be moved 130

from the position shown in Fig. 1 of the drawing to disengage one of the contact members 39 from the fixed contact member 19 and one of the contact members 41 from the contact member 22. If, as was hereinbefore set forth, contact member 21 is provided, engagement will be made therewith by the contact member 39 of the switch arm 38 with a snap action.

10 I provide, also, means for insuring positive movement of the part 26 upon movement of the part 24 to either of its limiting positions, this means including the lug 48 on one leg of the part 24, located in the recess 47 of the part 26. The relative dimensions of the lug 48 and the recess 47 are such that if, for any reason, the hereinbefore described action of the spring 37 and the toggle joint members 32 and 33 should not effect movement of the part 26, the lug 48 will strike the wall of the recess 47 and effect movement of the part 26 by direct and positive impact.

15 The device embodying my invention thus provides a relatively simple, compact centrifugally-actuable switch structure, the movable part of which embodies two resiliently-connected parts, one of which is movable directly in accordance with the radially outward movement of a weight member and the other part of the carriage being movable with a snap action to thereby disestablish or establish a circuit, with a minimum amount of arcing between the cooperating contact members.

20 Since various modifications may be made 25 in the device embodying my invention without departing from the spirit and scope thereof, I desire that only such limitations shall be placed thereon as are imposed by the prior art or are set forth in the appended claims.

25 I claim as my invention:

30 1. A transfer switch including a base plate, guides thereon, a two-part carriage movable in said guides, a pivotal connection between the two parts of said carriage at each end thereof, a resilient connecting means between the two parts of the carriage at one end thereof, lugs on one of said parts adapted to be engaged by a centrifugally-actuable means to move one part relatively to the base and a contact arm on the other part of said carriage.

35 2. A transfer switch including a base plate, guides thereon, a two-part carriage movable in said guides, means on one of said parts adapted to be engaged by a centrifugally-actuable weight to move said part, a resilient connecting means between the two parts of the carriage to cause movement of the second part of the carriage, with a snap action, 40 in response to movement of the first part of said carriage through a predetermined distance and a switch arm loosely mounted on the second part of the carriage.

45 3. A transfer switch including a base plate, guides thereon, a two-part carriage spaced

from the base plate and movable in said guides, two spaced sets of toggle-joint members connecting the two parts of the carriage and the base plate, a spring connecting the two parts of the carriage and effective to hold the carriage and the toggle-joint members in proper operative positions relatively to each other, laterally-projecting lugs on one of said parts of the carriage to be engaged by centrifugally actuable weight to move said part and a switch member mounted on said second part of the carriage.

4. A transfer switch including a base plate having laterally-projecting slotted guide portions, a two-part carriage slideable in said guide portions, laterally-extending lugs on one of the parts of said carriage to be engaged by a centrifugally-actuable weight member to move the part in direct accordance with the radial movement of a weight member, means operatively connecting the two parts of the carriage and the base plate comprising a spring extending between the parts of the carriage and a pair of toggle-joint members extending between the parts of the carriage and the base plate for causing movement of the second part of the carriage to be effected with a snap action upon a predetermined amount of movement of the first part of the carriage and a switch arm on the second part of the carriage.

5. A transfer switch including a base plate having laterally-projecting slotted guide portions, a two-part carriage slideable in said guide portions, laterally-extending lugs on one of the parts of said carriage adapted to be engaged by a centrifugally-actuable weight member to move the part in direct accordance with the radial movement of a weight member, means operably connecting the two parts of the carriage and the base plate comprising a spring extending between the parts of the carriage and a pair of toggle-joint members extending between the parts of the carriage and the base plate for causing movement of the second part of the carriage to be effected with a snap action upon a predetermined amount of movement of the first part of the carriage, means including an interfitting lug and recess on the two parts of the carriage for positively effecting movement of the second part upon predetermined movement of the first part and a switch arm on the second part of the carriage.

6. A transfer switch including a base plate having laterally-bent slotted guides thereon, a two-part carriage movable in said guides, means embodying a pair of toggle-joint members between the carriage parts and the base plate and a spring operatively connecting the parts of the carriage for ensuring movement of one of said parts of the carriage in advance of the second part and movement of the second part with a snap action, means

comprising an interfitting lug and recess on the two parts of the carriage for positively effecting movement of the second part of the carriage in response to movement of the first part of the carriage, and a switch arm on the second part of the carriage.

In testimony whereof, I have hereunto subscribed my name this 4th day of May, 1929.

HARRY D. ELSE.
